UNITED STATES PATENT OFFICE

162,880

SUSPENDED MILKER

Emanuel Rawson, Chicago, Ill.

Application June 20, 1949, Serial No. 3,406

Term of patent 14 years

(Cl. D23—1)

To all whom it may concern:

Be it known that I, Emanuel Rawson, a citizen of the United States, residing at Chicago, Illinois, have invented a new, original, and ornamental Design for Suspended Milker, of which the following is a specification, reference being had to the accompanying drawing, forming a part thereof.

In the drawing:

Figure 1 is a side view of a suspended milker, embodying my new design;

Figure 2 is a top view thereof; and

Figure 3 is a left-hand end view thereof.

A right-hand end view of the body of the milker of Figure 1 would show the milker as being of substantially the same shape as illustrated in the left-hand end view of Figure 3.

I claim:

The ornamental design for a suspended milker, substantially as shown and described.

EMANUEL RAWSON.
